UNITED STATES PATENT OFFICE

IRVING H. BERNSTEIN, OF NEW YORK, N. Y.

FABRIC-BOLT BOARD

Application filed July 27, 1927. Serial No. 208,756.

This invention relates to fabric bolt boards, such as are used in department stores, etc., for storing cloth and other fabrics on shelves.

In dry goods stores where a large number of bolts of cloth of different designs, colors and shades are stacked on shelves or tables, etc., it is very inconvenient to get a bolt at the bottom or near the bottom of a stack for the purpose of showing a customer a sample of the cloth contained in such bolt and it is generally necessary to remove all the bolts of cloth above the desired bolt in order to show the cloth.

The object of this invention is to provide a novel bolt board which will permit the showing of a sample of cloth from the end of the bolt board, without the inconvenience of removing other bolts of cloth as heretofore.

20 Fig. 1 shows the novel bolt board with cloth wound about it.

Fig. 2 is an enlarged fragmentary cross-sectional view of the device shown in Fig. 1.

Fig. 3 shows a modified form of the device.

25 Fig. 4 is a cross-sectional view of the device shown in Fig. 4.

Fig. 5 shows a further modified form.

Fig. 6 is a cross-sectional view of the form shown in Fig. 5.

30 Referring to Fig. 1, a bolt board 7 is shown having cut in one end thereof a groove 8, the groove being about $\frac{1}{8}$ inch deep, and 2 to $2\frac{1}{2}$ inches in width and over this groove is placed a metal plate 9 having therein a window 10, the plate being secured to the end of the bolt board by nails or other suitable means and the outermost surface of the plate being flush with the surface of the end of the bolt board.

40 Several layers of cloth are wound about the board in the usual manner and a sample strip of the cloth 11, cut from the end of the outermost layer, about two inches wide, is forced between the first layer of cloth and the board 45 until this strip 11 extends a considerable distance along the board beneath the layers of cloth wound thereon, a ruler or yard stick being conveniently used for this purpose.

As will be seen in the drawings, a portion 50 12 of the strip of cloth may be allowed to

extend beyond the end of the bolt board and this extended portion is inserted in the groove 8 between the plate 9 and the end of the board, as shown in Fig. 2 for exhibition through the window, which is of lesser length than the width of the cloth strip. 55

In order to facilitate grasping of the end 12 of the strip, the lower portion of the board at the groove 8 is notched as shown at 18.

Now when it is desired to obtain a sample 60 of the cloth, all that is necessary to do is to pull a portion of the strip 11 outwardly and cut off the necessary sample, and it is to be noted that numerous samples may be cut from the strip without waste. The lower 65 edge of the metallic plate 9 may be used for cutting such samples, and the plate 9 may be provided with a cutting edge 20 to facilitate this operation.

70 In Fig. 3 is shown a modified form in which no groove is cut in the board, but fixed to the end of the board is a metallic plate 13 having a raised portion 14 in the centre thereof and a window 15 in this raised portion. The raised portion 14 provides a space between the plate 13 and the end of the board corresponding to the groove 8 shown in Fig. 1 and the sample to be shown is manipulated in the same manner. 75

75 In Fig. 5 is shown a further modification 80 in which the bolt board is provided with a slot 17 extending completely through the board adjacent its end, as shown in detail in Fig. 6 and the desired sample 12 is manipulated in the same manner to appear through an opening 19, in the end of the board to intersect the slot 17. 85

85 From the above it will be seen that there has been provided a novel and convenient means for displaying cloth wound upon bolts 90 without the necessity of taking down a large number of bolts of cloths in order to have access to the desired cloth.

90 The improved bolt board obviously will save much time in the sale of fabrics, and also 95 enable the stacking of bolts of cloths in an orderly manner without the necessity of disturbing the stack whenever it is merely desired to show a sample of cloth in any particular bolt. 100

I claim:

1. In a fabric bolt board having a groove in the end thereof, a plate fixed to the end of the board and covering the groove, said plate having a window therein communicating with said groove and a sharpened edge for cutting fabrics passing through said groove.
- 5 2. A fabric bolt board having a groove in the end thereof, the groove being enlarged near the lower surface of the board, and a plate fixed to the end of the board and having a window therein communicating with said groove for displaying a sample of the fabric taken from the board passing through said groove.

Signed at New York, in the county of New York and State of New York, June, 1927.

IRVING H. BERNSTEIN.
